UNITED STATES PATENT OFFICE.

HIRAM S. MAXIM AND JAMES RADLEY, OF NEW YORK, N. Y.

HEAD-LIGHT.

Specification forming part of Letters Patent No. 95,248, dated September 28, 1869.

To all whom it may concern:

Be it known that we, HIRAM S. MAXIM and JAMES RADLEY, both of the city and county of New York and State of New York, have invented certain new and useful improvements in apparatus for making illuminating-gas from gasoline or other analogous fluids and in the application of the same to the lighting of locomotive head-lights; and we do hereby declare that the following is a full and exact description thereof, reference being had to the accompanying drawings, and to the figures and letters marked thereon—

Figure 1 being a vertical section of the apparatus through the focus of the parabolic reflector of a locomotive head-light and at right angles with the axis of such reflector; Fig. 2, a horizontal section of the apparatus through the axis of the reflector.

The same letters of reference are used to indicate the same parts in both figures.

The nature of our invention consists in such improvements in apparatus for vaporizing and converting hydrocarbon fluids into illuminating-gas as to greatly reduce the bulk of such apparatus and to make it particularly suitable to the purpose of lighting locomotive head-lamps and in its application thereto.

To enable others skilled in the art to make and use our invention, we shall proceed to describe its construction and operation, first observing that the hydrocarbon oil or fluid we propose to use in this apparatus has a specific gravity of from .70° to .80°, which is too heavy for common gas-machines and too light to be used with safety in wick-lamps. This description of oil is very abundant and cheap, as it is as yet but little used. It is with special reference to the vaporizing and consuming of this oil that we have adapted our apparatus, and by which it is converted into an illuminating-gas of great brilliancy and power, particularly suitable for the head-lights of locomotives. We shall therefore describe an apparatus which we have designed for that special purpose.

In this apparatus, A is the tank for holding the oil or gas fluid, made of sheet-iron or other suitable material, of cylindrical form, and of sufficient strength to resist an internal pressure of about sixty pounds to the square inch. When ready for use this vessel should be about half-filled with the oil, and the remaining half

with air compressed to about thirty pounds to the square inch.

We usually pump the air into the tank first to a pressure of about fifteen pounds to the square inch, and then pump in the gas-fluid. Both the air and the oil may be forced in with the same pump, which is attached for that purpose to the nozzle B of the filling pipe C, Fig. 2, which pipe is furnished with a stop-cock, D, near the nozzle B, to retain the air and oil thus forced into the tank. From the tank A the hydrocarbon oil is forced by the pressure of the air in the tank through the tube E into the heating-chamber F, and from thence through the small passages in the vaporizer G, as shown in section in Fig. 1, which passage is controlled and closed, when required, by the screw-valve H.

The vaporizer G is of brass, and has an annular-shaped passage around it, through which a current of steam or hot water or other suitable fluid in a heated state is made to pass by directing the small induction-tube J, which connects with the boiler, into the annular passage around the vaporizer to one side of the eduction or return pipe K, also connecting with the said annular space or passage. The tube J being inside of the return-pipe K, both tubes being made to connect with the globe L, but at opposite sides of it, the induction-pipe passing through the globe to its connection with the boiler, but the eduction-pipe connecting with the interior of the globe L, the steam or hot water makes its exit by the outlet-pipe M. The carbon oil having assumed a gaseous form in its passage through the vaporizer G, it enters the lower end of the gas-pipe N in an upward direction and at a high velocity, by reason of the pressure of air in the tank A. A few small holes being made around the lower part of the gas-pipe N, the atmospheric air is drawn into this gas-pipe through these holes by the action of the jet of vapor from the contracted vent upon the interior of the tube. The hydrocarbon vapor and the atmospheric air, being commingled and combined with each other in the gas-pipe N, pass up to the mixer P, which is formed by plugging the upper part near the end of the gas-pipe N and constructing a small annular chamber around it, the pipe N communicating with this annular chamber by a few small holes below the top plug, the annular chamber in like manner communi-

eating with the portion of the pipe N which is above the plug, being the passage from the mixer P to the burner R. The upward current of the gas being thus interrupted by the top plug in the pipe N, and made to pass off to the annular chamber P through the small lateral openings below the plug, and then made to pass from the annular chamber to the pipe N above the plug, the elements of the gas are completely intermingled by the regurgitation or commotion thus produced. The carbon vapor and atmospheric air thus combined enter the pipe N above the plug and pass immediately to the burner R as an illuminating gas.

The burner shown at R, Fig. 1, is of the Argand pattern, as that style of burner is considered best where strength and purity of flame are important, as in locomotive head-lights; but any form of burner may be used. In this apparatus the size and power of the flame are regulated, and the flame may be extinguished when required, by the screw-valve H.

The air-trunk S of the burner or lamp R is formed by continuing the brass cylinder in which the heating-chamber and vaporizer are constructed to the proper height for carrying the glass chimney T, and it is fitted with a rabbit for that purpose. This trunk is also perforated with numerous small holes for the air to pass in to supply the flame at R, as well as the gas-pipe N.

In applying this apparatus to a locomotive head-light the contracted vent and air holes in the gas-pipe N may be dispensed with, as the connection between the vaporizer G and burner R, being short, is sufficiently hot to preserve the vapor from condensation. It will therefore in such case make an excellent illuminating-gas without the introduction of the atmospheric air into the gas-pipe N, as the air will combine with the warm hydrocarbon vapor as it issues from the apertures of the burner.

The apparatus herein described is designed for illuminating locomotive head-lights, but the same mode of construction and operation may be employed for domestic purposes by using the steam or hot water from the ordinary kitch-

en-range or water-back as the vaporizing agent, or a small heater may be employed for this purpose, which might be heated by a small gas-burner, or in any other convenient manner; and with such a heater this apparatus could be used with good effect for illuminating lighthouses, as the flame is very pure and has great brilliancy and power.

Having thus described our improvements in apparatus for making gas from gasoline and other analogous fluids and adapting the same to the lighting of locomotive head-lamps and other purposes, what we claim as our invention, and desire to secure by Letters Patent, is—

1. The combination of the vaporizer with a steam or hot-water chamber or passage in such wise as to vaporize a small continuous stream of the carbon oil, in the manner and for the purpose substantially as herein described.

2. The combination of the vaporizer with the steam-boiler of a locomotive for the purpose of making and supplying an illuminating-gas from gasoline or other hydrocarbon oils or fluids for the head-light of such locomotive, constructed and operating substantially as herein described.

3. The combination of the induction and education pipes with the heating-chamber around or at the vaporizer by passing the induction through the return pipe, substantially as herein described.

4. The combination of the heater and vaporizer with the air-trunk which carries the chimney of a locomotive head-light, so as to secure sufficient heat to the vapor to maintain its gaseous form in its passage from the vaporizer to the burner, in the manner and for the purpose substantially as herein described.

5. The combination of the mixer with the gas-pipe and its contracted vent and air holes, constructed and operating substantially as herein described.

HIRAM S. MAXIM.
JAS. RADLEY.
